(57) **CLAIM**

The ornamental design for an adapter for charging device for portable electronic apparatus, as shown and described.

DESCRIPTION

FIG. 1 illustrates a perspective view of an adapter for charging device for portable electronic apparatus showing my new ornamental design;

FIG. 2 illustrates a front view thereof;

FIG. 3 illustrates a rear view thereof;

FIG. 4 illustrates a left side view thereof;

FIG. 5 illustrates a right side view thereof;

FIG. 6 illustrates a top view thereof;

FIG. 7 illustrates a bottom view thereof; and,

FIG. 8 illustrates a perspective reference view thereof.

The portions indicated in broken lines in FIG. 8 are for illustrative purposes only and form no part of the claimed design.
